UNITED STATES PATENT OFFICE.

WILLIAM T. VAN DORN, OF CHICAGO, ILLINOIS.

RAILWAY-CAR.

SPECIFICATION forming part of Letters Patent No. 658,031, dated September 18, 1900.

Application filed November 4, 1899. Serial No. 735,745. (No model.)

To all whom it may concern:

Be it known that I, WILLIAM T. VAN DORN, a citizen of the United States, residing at Chicago, county of Cook, State of Illinois, have invented a certain new and useful Improvement in Railway-Cars; and I declare the following to be a full, clear, and exact description of the invention, such as will enable others skilled in the art to which it pertains to make and use the same, reference being had to the accompanying drawings, which form a part of this specification.

My invention has for its object the production of mechanism to prevent the derailing of railway-cars.

The invention is applicable to either what are generally known as "steam-railroads" or to "street-railways."

It consists in a combination of devices and appliances hereinafter described and claimed.

In the drawings, Figure 1 is a side elevation, with parts in section, of a railway-car axle and adjacent mechanism. Fig. 2 is an end elevation of the same on a reduced scale.

In carrying out the invention, A represents the car-axle; B, the wheel; C, the journal-box; D, the rail, and E the railway-ties.

The above parts are of the usual or ordinary construction, and as my invention is applicable to any of the ordinary or usual forms or constructions of railway-cars I have only shown the parts mentioned.

Instead of the axle terminating in the journal-box C, as is ordinarily the case, I extend the axle through the end of the journal-box and key to it in any suitable manner—as, for instance, by the set-screws f—two collars F. Between these and journaled on the axle is what may be termed an "antifriction-roller" G.

H represents one of a series of arms or braces, preferably made of angle-iron in cross-section to give the requisite strength, securely engaged to the tie E, on which the rail D rests, by bolts H" and a plate H', the idea being to make the arm H so securely engaged to the tie that any elevations or depressions of the tie will carry the arm with it. The arm is extended upward and laterally and is provided on its under side with a rail J, the head j of the rail being closely ad-

jacent to or, if desirable, in contact with the antifriction-roller G.

The operation of the mechanism is obvious. Should the wheel B attempt to leave the rail D, the roller G will at once come in contact with the rail J, and any further elevation of the wheel D will be thereby prevented, so that with my device as just described the derailing of the car is impossible.

Of course the antifriction-roller G might, if desired, be dispensed with and the rail J brought down, so that it will bear directly on the axle; but as more or less friction will be developed when the axle comes in contact with the rail J it is perhaps desirable to provide the antifriction-roller G. So, also, if desirable, the arms H might be strengthened or braced by any of the well-known means in the art without departing from the spirit of the invention. So, also, while I prefer to extend the axle to form the bearing against the rail J yet any other form of bracing-arm might be extended from the car to come in contact with this rail J, the idea being to provide on the car some sort of an extending arm which will come in contact with a continuous surface along the road-bed and prevent the abnormal elevation of the car-wheels from the track.

What I claim is—

1. In a railway-car, the combination with the rotary axle thereof and its journal-box said axle projecting laterally beyond the journal-box, of a continuous rail or track above the end of the axle with which it can come in contact when the axle is abnormally elevated, substantially as described.

2. In a railway-car, the combination with the journal-box and the rotary axle extended laterally beyond the journal-box and provided on its end with an antifriction-roller, of a continuous rail or track above said roller against which the roller can bear when the axle is abnormally elevated, substantially as described.

In testimony whereof I sign this specification in the presence of two witnesses.

WILLIAM T. VAN DORN.
